UNITED STATES PATENT OFFICE.

MARTIN C. BRIGHT, OF INDIANAPOLIS, INDIANA. ASSIGNOR OF ONE-HALF TO SAMUEL M. BRUNDAGE, OF INDIANAPOLIS, INDIANA.

STARTER FOR EXPLOSIVE-ENGINES.

1,082,261.

Specification of Letters Patent.

Patented Dec. 23, 1913.

Application filed January 25, 1912. Serial No. 673,402.

To all whom it may concern:

Be it known that I, MARTIN C. BRIGHT, a citizen of the United States, residing at Indianapolis, in the county of Marion and State of Indiana, have invented certain new and useful Improvements in Starters for Explosive-Engines, of which the following is a specification.

This invention relates to improvements in starters for hydro-carbon engines, and the object is to provide means for supplying a hydro-carbon explosive mixture when the engine is at rest, to that one of a plurality of cylinders of the engine, which, in its regular running sequence, should be the next cylinder to be fired.

A further object is to provide a simple and inexpensive device that can be attached to a magneto-generator and operated from the spark-contributer shaft of the latter which is timed with the cycles of the engine, and my explosive mixture supplying device thereby timed with both the engine and the magneto.

The object, also, is to provide means for the independent adjustment of my device to time it with the magneto and engine.

I accomplish the above objects by the mechanism illustrated in the accompanying drawing, in which

Figure 1 is a vertical section on the line 3-3 of Fig. 2 through the axis of the distributor-shaft of the magneto having my invention applied thereto. Fig. 2 is an end elevation of the mechanism illustrated in Fig. 1 showing same diagrammatically connected up with a pump and also with the cylinders of a four-cylinder engine, and Fig. 3 is a vertical cross section on the line 40 b-b of Fig. 1.

Like characters of reference indicate like parts through the several views of the drawing.

1, 2, 3, and 4, are the respective cylinders of a four-cylinder gasolene engine. As my device may be used with an engine having a greater or less number of cylinders it will be understood that a four-cylinder engine is only shown here by way of illustration.

50 5 is a magneto of any usual and suitable type, in which 6 is the armature shaft which is connected by a worm and gear 7 with the crank-shaft 8 of the engine. Other ap-

proved driving connections than a worm and gear may be used if desired.

9 is the mechanism of the magneto for distributing an interrupted current of electricity, producing a spark at the ignition-plugs (not shown) of the respective engine cylinder. The electric current distributing mechanism 9 comprises a rotary traveling member which is mounted on a shaft 10 and is suitably insulated therefrom, and on the opposite end of shaft 10 my hydro-carbon distributing device is mounted.

My hydro-carbon distributing device comprises a cylindrical case 11 preferably having its outer end 12 cast integrally with said cylindrical sides, and having an external flange 13 at its opposite end by which the case is bolted to a case extension 14 which latter is bolted to the magneto. The inner end of the case 11 is screw-threaded on its inner side to receive an externally screw-threaded circular head 15. The head 15 has a central bore for the passage through it of an extension 17 of the distributor-shaft 10. The shaft-extension 17 has a reduced and screw-threaded inner end 16 which screws into a suitable screw-threaded opening in the end of shaft 10. The shaft-extension 17 is provided with a screw-thread adjacent to the reduced end 16, opposite in direction to the thread on said reduced end, that is, 16 being provided with a right-hand thread then the adjacent portion of shaft extension 17 will be provided with a left-hand thread. Screwing upon the threaded-end of 17 is a metal bearing-sleeve 18, and between the end of shaft 10 and the sleeve 18 is a split lock-washer 19. This provides means for holding any desired rotary adjustment of extension 17 with relation to the distributor-shaft 10, in timing the valve of my hydro-carbon distributor, hereinafter to be described, with the electric current distributor of the magneto. A suitably extended hub of the head 15 is screw-threaded to receive a follower 20 which holds a packing by which a tight joint is secured around the bearing-sleeve 18. The head 12 has a boss-extension 21 which is hollow to receive the end of shaft-extension 17 and form a bearing-support for the latter. The extreme end of shaft-extension 17 is squared, as shown, to engage a wrench, when the

casing 11 is removed, for the purpose of rotating the extension 17 in setting it with shaft 16, as above described.

Formed through the head 12 are four equidistant ports 1^a, 2^a, 3^a, 4^a, which are connected by pipes 1^b, 2^b, 3^b, 4^b with the outer ends of the respective cylinders 1, 2, 3 and 4, for the discharge therethrough of a hydro-carbon mixture to the interior of the case 11.

Mounted upon the shaft-extension 17 is a valve 23, in the form of a circular disk. A spline 24 seated in the extension 17 and entering a way in the hub of the valve 23 permits a sliding adjustment of the valve 23 longitudinally of the shaft-extension 17, but compels the valve to rotate with said shaft. The side of the valve 23 which contacts with the head 12 makes a close moving fit therewith, and the valve 23 is pressed constantly against the head 12 by a spring 24'. The valve 23 has a single port-hole 25 which discharges into a groove or channel 26 in the side of valve 23 which contacts with the head 12. This channel 26 is curved in the arc of a circle which is concentric with the axis of shaft-extension 17 and it and the port-holes 1^a, 2^a, 3^a, 4^a are so located that the channel 26 passes across each port-hole at every revolution of the valve-plate 23. The arc covered by the length of the channel 26 is less than 180°, as shown by dotted lines in Fig. 3, which enables it to reach from one port-hole in head 12 to another adjacent one but does not provide such communication between three ports. Discharging into case 11 is a pipe 28 through which an explosive hydro-carbon mixture is discharged into the case from a pump 29, or from other suitable instrumentality by which this mixture under pressure may be supplied.

The operation of my improved starter is as follows: Assuming that the engine has stopped with the pistons in the positions which are generally about as illustrated in Fig. 2, cylinder 1 will be ready to fire, 2 will be exhausted, 3 will be compressing, and 4 will be ready to take in gas; then assuming that the valve-plate 23 is set with relation to the magneto and engine to cause it to stop with the engine with its port 25 and channel 26 in communication with ports 1^a and 3^a as shown in Fig. 3, then, a hydro-carbon mixture supplied to the case 11 through pipe 28 will be supplied through port 25, channel 26 and pipe 1^b to the cylinder 1, next in regular sequence to be fired, and also to cylinder 3 to replenish the explosive mixture which has probably leaked out if the engine has stopped long, and is compressing to be fired next. The explosive mixture thus introduced into the cylinder 1 will be fired by a spark from the usual permanent battery (not shown) which is timed

by passing through the magneto distributor. In this way the proper cylinder of an engine will be charged independently of the carbureting mechanism which is relied upon for that work after the engine has started.

Should the engine happen to stop with one of the cylinders other than cylinder 1 ready to fire, the valve-plate 23, being timed with the magneto and engine, will stop with its port 25 and channel 26 in open communication with that cylinder, whichever one it may be.

While I have described my invention with more or less minuteness as regards details of construction and arrangement, and as being embodied in certain precise forms, I do not desire to be limited thereto unduly or any more than is pointed out in the claims. On the contrary, I contemplate all proper changes in form, construction, and arrangement, the omission of immaterial elements, and the substitution of equivalents, as circumstances may suggest or necessity render expedient.

I claim—

1. An explosive engine having a plurality of cylinders, a crank-shaft driven therefrom, a magneto-generator driven from the crank-shaft and timed with the cycle of the engine to properly deliver a spark to ignite hydro-carbon charges therein, a second shaft driven from and timed with the magneto, a chamber holding a hydro-carbon mixture under pressure, said second shaft entering said chamber, said chamber having as many discharge ports as there are engine cylinders, arranged around the second shaft, conduits from the discharge ports to the respective cylinders, a valve-plate mounted on the second shaft and contacting with the chamber-wall having the discharge ports, said valve-plate having a port to successively register with those in the chamber-wall and also having a curved channel in the contacting side from its port to increase the opening time with the ports in the chamber-wall.

2. In an explosive engine having a plurality of cylinders, a crank-shaft driven therefrom, a magneto-generator driven from the crank-shaft and having a distributor to distribute an interrupted electric current to the respective cylinders in proper sequence to fire the hydro-carbon charges in the latter, a rotating distributor-shaft, a chamber holding a hydro-carbon mixture under pressure, into which said chamber an extension of the distributor-shaft terminates, said chamber having as many discharge ports as there are engine cylinders, arranged around the distributor-shaft extension, conduits from the port openings to the respective cylinders, and a valve-plate mounted on said distributor-shaft and contacting with the chamber-wall having said discharge ports, said valve-plate having a port to successively

register with the ports in the chamber-wall, and also having a curved channel to increase the opening time between the port of the valve and the successive ports of the chamber-wall.

3. An explosive engine having a plurality of cylinders, a crank-shaft driven therefrom, a magneto-generator driven from the crank-shaft and having an electric current interrupter and distributor, a rotating distributor shaft, a chamber within which said distributor shaft terminates, a wall of said chamber having as many port holes as there are engine cylinders, arranged in a circle concentric with the said distributor shaft, conduits connecting the port holes with the respective cylinders, a valve-plate mounted on the distributor shaft and contacting with the chamber-wall having ports, said valve-plate having a single port to successively register with the ports of the chamber-wall and terminating in a channel in the inner wall of the valve-plate to increase the time of port opening, means to adjust the valve-plate to advance or retard the registration of its port with the ports of the chamber-wall, and means for supplying an explosive mixture to the chamber under pressure.

4. An explosive engine having a plurality of cylinders, a crank-shaft driven therefrom, a magneto-generator having a distributor-shaft and a distributor, a chamber containing an explosive mixture under pressure, a wall of the chamber having as many port holes as there are engine cylinders, pipes connecting the port holes with the respective cylinders, an extension from the distributor shaft entering the said chamber, a valve-plate mounted on the shaft-extension to rotate with the latter and having a single port hole to register successively with the port holes in the chamber-wall, means for holding the valve-plate elastically in contact with the chamber-wall having said ports, and means for making a rotary adjustment between the distributor shaft and the shaft-extension therefrom.

In witness whereof, I, have hereunto set my hand and seal at Indianapolis, Indiana, this sixteenth day of January, A. D. one thousand nine hundred and twelve.
